UNITED STATES PATENT OFFICE.

WILLIAM J. RENNIMAN AND WILLIAM C. CAREY, OF AVOCA, PENNSYLVANIA.

DESIGN FOR A CHIMNEY-CAP.

SPECIFICATION forming part of Design No. 22,914, dated November 21, 1893.

Application filed October 7, 1893. Serial No. 487,505. Term of patent 7 years.

To all whom it may concern:

Be it known that we, WILLIAM J. RENNIMAN and WILLIAM C. CAREY, citizens of the United States, residing at Avoca, in the county of Luzerne and State of Pennsylvania, have invented a certain new and original Design for Chimney-Caps, of which the following is a specification, reference being had therein to the accompanying drawings, in which—

10 Figure 1 is a perspective view of the cap, and Fig. 2 a vertical sectional view of the same.

The leading feature of our design is a rectangular cap having a central opening and provided entirely around its edges with a depending continuous flange and on its upper surface with a series of short arrow-pointed posts, as more fully hereinafter set forth.

15 In the drawings, A designates the metal cap, which is rectangular in shape and has a

rectangular opening in its center. A depending flange a is formed on the outer edges of the cap and extends continuously entirely around the same. Around the opening on the upper surface is secured a series of short ²⁵ posts, which are slightly rounded at their lower ends and arrow-pointed at their upper ends, as shown.

Having thus fully described our invention, what we claim is—

20 The design for a chimney cap herein shown and described.

In testimony whereof we affix our signatures in presence of two witnesses.

WILLIAM J. RENNIMAN.
WILLIAM C. CAREY.
